UNITED STATES PATENT OFFICE

FREDERICK EUGENE PERNOT, OF LONDON, ENGLAND

MULTICHANNEL TELEGRAPHY

Application filed August 4, 1926, Serial No. 127,141, and in Great Britain August 15, 1925.

The present invention has reference to methods and devices for operating submarine cables or other telegraph circuits in such a way as to permit the operation over a single circuit of substantially independent channels of communication. Such a procedure is desirable both from the traffic handling point of view as well as for the reason that in those cases where the gross signalling capacity of the cable or circuit is much in excess of the speed which can be effectively dealt with either by existing types of apparatus or the human operators, this excessive speed can be divided into two or more channels each operating at a convenient moderate speed.

The system proposed in the present invention is specially applicable to the signalling code known as "recorder" or "cable" code, but is also applicable to any code wherein all signal or code elements are of equal duration or multiples of some common duration.

The principal feature of the present invention consists in the provision in a synchronous, multi-channel system of telegraphy of means whereby the individual channels can be operated at different speeds.

A further feature of the invention consists in the operation of the several individual channels at speeds which are integral multiples of some common fundamental speed, or in other words at speeds which constitute vulgar fractions of the gross speed.

A further feature of the invention consists in the provision at the transmitting end of the telegraph circuit destined to carry the aggregated signals of means for combining the signals of the several individual channels and in the provision at the receiving end of means for the segregation of the aggregated signals into component channels.

Another feature of the invention consists in the provision in the aggregating and also in the segregating mechanisms of a moving member repeating cyclic motions at a speed (frequency) equal to a common divisor of the individual signal speeds in the separate channels.

Yet another feature consists in the provision in the mechanism of a number of sets

of selecting devices, the number of sets being equal to the number of circuits operating the mechanism, and the selecting devices in the several sets being in the same ratio as the respective speeds of the individual circuits.

Another feature of the invention consists in the provision of a number of sets of transmitting mechanisms, the number of sets being equal to the number of circuits to be fed and the number of transmitting mechanisms in the several sets being in the same ratio as the respective speeds of the individual circuits.

Another feature consists in arranging the transmitting mechanisms in such a manner that they are set up (that is positioned) each one by a corresponding selector mechanism so as to transmit the same kind of signal as originally actuated the selector mechanism.

Further features consist in causing each of the selector mechanisms in each set to be actuated in turn by the signal elements present in the circuit supplying the set, and in providing adjustments enabling the selection to be determined by the kind of signal element present during a short interval of time located as desired within the normal period of time occupied by a signal element.

Another feature of the invention consists in the provision of means for temporarily storing the signal elements represented by the positioned selecting and transmitting mechanisms and in causing the transmitting mechanisms in each set to send out the signal elements to its circuit at uniformly spaced time intervals.

Further features of the invention will be apparent from the accompanying description and the drawings, wherein:—

Fig. 1 shows two series of signals and the details and effect of their combination into a single circuit.

Fig. 2 is adapted to illustrate the principal features essential to systems capable of operating different channels at different speeds.

Fig. 3 shows in detail a type of mechanism adapted to working different channels at speeds which may be different.

Fig. 4 illustrates a conventional form of

"jockey" for holding a moving member in either of two positions.

Fig. 5 shows the details of a transmitting key referred to in Figure 3.

Fig. 6 shows the usual way of connecting two keys for the transmission of "cable code" signals.

Fig. 7 shows a mechanical type of selecting mechanism.

Fig. 8 illustrates in end view the deflecting wheels and driving members indicated in Fig. 7.

Fig. 9 illustrates an alternative and cam-operated type of selector and transmitting mechanisms, and

Fig. 10 shows a further alternative mechanism based upon the use of segmental conducting slip rings.

Figures 1, 2 and 3 are to be considered together in the description of a system for working several channels at different speeds over a single circuit.

In Fig. 1 at X and C are shown in recorder code the letters A, B, C, D, etc., the signals C being at one and one-half times the speed of signals X; that is, the speeds are in the ratio 3:2, for example, signals X at 600 center holes per minute and signals C at 400 center holes per minute.

Fig. 2 shows schematically mechanisms for combining and separating the two series X and C of signals shown in Figure 1 and Figure 3 shows in detail a method of constructing the apparatus depicted in Figure 2.

In Figure 2, C and E constitute the terminals of a system delivering signals to receiving system A. The receiving system A is constituted in this case by a regenerator system such for instance as described in U. S. patent application No. 671,136, and the result of such reception is to deliver perfectly formed signals (as at C in Fig. 1) over leads 5, and also to maintain the shaft and gear 4 running in synchronism with the arriving signals.

For purposes of illustration it is assumed that at the station containing receiver A there is also located a transmitter X which, by means of gears 1, 2, and 3 is driven in synchronism with regenerator A, so that for every 3 center holes received over the cable C there are formed two center holes at transmitter X. Signals from transmitter X are delivered over leads 6, and thus the signals shown at X and C in Fig. 1 are representative of the signals delivered over leads 6 and 5 respectively in Figure 2.

Taking the signal speeds to be 400 center holes and 600 center holes respectively from sources A and X, the greatest common divisor of these speeds is 200, and by gearing 1 and 2 the shaft 4 is driven at this speed. In Figure 2 the signals over leads 5 and 6 are delivered to magnets 8 and 7 respectively. In the detailed drawing Figure 3, the shaft 4 represents the shaft 4 of Figure 2, and the

leads 5 and 6 of Figure 2 are shown as 5', 5'', and 6', 6'' respectively in Figure 3. Leads 5' and 6' are for dot currents and leads 5'' and 6'' are for dash currents; dots and dashes appearing in separate circuits as is well known in the art.

In Figures 2 and 3, shaft 4 carries two discs or members R' and R''. Pivoted armatures are mounted radially on the faces of the discs as shown in Figure 3 in detail at 6' and 6'' and as further indicated at d' and d'', a' and a'', and c' and c''. Each armature carries a contact as at 9', arranged to make contact at 10' when, through an agency precisely to be described, the armature is pulled away from the disc. A roller jockey 11' holds the armature in either of its two positions, the jockey being for example of the usual type shown in Figure 4, comprising a roller 11 pressed by a spring 13 against a projection 12 of the movable armature. All of the armatures are similar, so description of one only suffices.

The magnet 7' of Figure 3 is fixed in position (but adjustable as hereinafter referred to) facing the disc R' so that when, consequent upon rotation of the latter, the armature b' passes in front of the magnet poles (the magnet being energized by a signal current) it will be attracted by the latter and pulled away from the disc, thus establishing circuit through contacts 9' and 10'; but this attraction and deflection of the armature b' only takes place when a dot signal is present causing current to flow from leads 6' through the winding of magnet 7'. Being deflected, the armature b' remains so because of jockey 11 until nearly an entire revolution of the disc R' is completed, whereupon the armature b' passes a restoring member 14' which forces it back into its normal position ready to be again deflected if a signal current is present in magnet 7' at the next instant of passage in front thereof. The restoring members 14' and 14'' are mounted on the frame 15 carrying magnets 7' and 7'', so that the entire system of magnets and restoring members is rotatable as a whole about the axis of the shaft 4, thus enabling adjustment to be made causing the armature to pass in the front of the magnets at about the middle of the time interval of a signal; this being the instant when the signal is least likely to be affected by distortion.

When contacts 9 and 10 come together current flows from battery or source 16 through slip rings 17 on the shaft 4 through leads 19', 20, and 21 thus energizing magnet 22' and thereby attracting armature 23' and causing the pin 24', engaged with armature 23' to be pushed to the right so as to co-act with member 25'. Magnet 22', armature 23' and pin 24' are all carried on a spider 27 rotated along with the shaft 4. Member 25' is described in Figure 5 and is there shown as a

lever 25 mounted in a bearing 34 and retained by a spring 28 against stop 35 in the position shown whereby contact is affected between its rearward projection 29 and contact stud 31. The pins 24 in Figure 5 move in the circular orbit shown, and are those of which one is shown at 24' in Figure 3, and are arranged so that when they are set into operative position (by armature 23' etc. in Figure 3) they engage the end of lever 25 and move same downwards, thus causing member 29 to make contact with stud 30. The arc θ of the portion of the lever engaged by the pins 24 is made equal to 360 degrees divided by the number of pins as a maximum but a lesser amount if it is desired to transmit discrete (non-block) signals from the mechanism.

Two keys, one on either side of the disc and each as described in Figure 5 and as controlled by levers 25' and 25'' shown in Figure 4 are connected to send out cable code signals. The connections are effected in the usual way indicated in Figure 6, where circuit 33 is fed through the two keys 29' and 29'' from source 32.

In brief, a dot signal being present in circuit 6' energizes magnet 7. Armature b' is attracted when it passes in front of magnet 7' and closes contact 9'-10' thus energizing magnet 22' and extruding pin 24' into the way of key lever 25'. Armature b' , because of jockey 11', is held in deflection for nearly an entire revolution of the shaft 4, and hence pin 24 is likewise held in operative position for the same time, and whilst it is so held it effects the transmission of a signal through the key attached to lever 25' as described.

Similarly a dash signal in circuit 6'' affects magnet 7'', armature 6'', magnet 22'', pin 24'' and finally lever 25'' to cause a dash to be sent out from the key attached to lever 25''.

With reference again to Figure 2, disc R' carries two sets of selectors (armatures and contacts as described at b' and b'' in Figure 3) namely b and d , and since the disc rotates at 200 R. P. M. whilst the signals arrive in magnets 7 at the rate of 400 center holes per minute, it is apparent that first selector b will be set in position by one signal and then half a revolution later selector d will be positioned by the following signal. Similarly disc R'' carries three selector mechanisms a , c , and e and since as stated signals arrive in magnets 8 at the rate of 600 center holes per minute, the armatures of the selectors a , c , and e will be positioned successively by successive signals.

The disc or frame 27 carries magnets and transmitting pins a , b , c , d , e , (being arranged as described at 27, 22, 23', 24' and 26' in Figure 3), and these pins are set up to effect transmission as described in Figures 3, 5, and 6 by the selectors a , b , c , d , and e respec-

tively; transmission being effected through the key system 25 to leads 36 and 37 and thence over single cable or circuit 38.

In Figure 1, the signals at X and C represent those delivered from the two separate sources to magnets 7 and 8 respectively of Figure 2. The time interval between vertical lines m and n represents the time of one complete rotation of shaft 4 in Figure 2, and this time includes precisely two center holes of signals X and three center holes of signals C. The vertical line O represents the instant at which the mechanism of Figure 2 is in the position there indicated. It is to be noted that instant O occurs at the middle of the signal elements a of signals C. This is the precise instant when the signal element is least likely to distortion and therefore, by reference to Figure 2 it is found that selector a on disc R'' is directly opposite its magnet 8 to be in position for selection (or positioning of its armature) to take place.

It is in order to be able to readily secure such a condition that magnet system 8 is made adjustable in angular position about shaft 4 and disc R''. A slight further rotation of shaft 4 brings selector b of disc R' opposite its magnet 7, and by reference to Fig. 1 it is seen that at an instant slightly later than that of vertical line O the middle of signals X occur.

Briefly, therefore, in Figure 2 the signal elements b and d of signals X and the signal elements a , c , and e of signals C act to set up the corresponding selectors a , b , c , d , and e of Figure 2. These selectors in turn set up the corresponding transmitting pins a , b , c , d , and e , which, acting in turn through key system 25 send out the series of signals Z in Figure 1. The time interval between vertical lines p and q is the time required to transmit the combination of signals X and C received by magnets 7 and 8 of Figure 2 during the time interval m to n . Signal elements a , b , c , d and e of the signals Z correspond respectively to signal elements a , b , c , d , and e of the separate series X and C, and for purpose of illustration, signals are shown indicating the form which would be assumed by the combined signals Z if no signals arising from cable C in Figure 2 were present.

Key system 25 of Figure 2 is made adjustable in angular position about the shaft 4 in order that the transmission of any signal element can be made to take place during the time the transmitting pin is held positioned for such element.

Although the description so far has been based upon the assumption that perfectly formed signals are delivered to electro-magnets 7 and 8 as shown in Figure 2, as from regenerator A and transmitter X, the arrangement of the apparatus as shown is capable of dealing equally well with distorted

signals. Regenerator A may therefore be dispensed with provided synchronism is maintained in some way between the two series of signals which are to be combined and the described apparatus for combining. When so used the apparatus accomplishes regeneration of the signals as well as their combination, and it is to be understood that the signal sources A and X shown in Figure 2 are only illustrative: the two series of signals may arise from local transmitters, a cable circuit and a local transmitter, or two cable or other circuits equally well provided, synchronism is maintained. It is apparent also that signals from more than two sources may be combined according to the method described, it being only necessary to provide a disc similar to R' or R'' with the appropriate number of selectors for each additional channel, and then on disc 27 to provide the additional transmitting magnets.

The series of signals Σ in Figure 1 being delivered to the cable 38 in Figure 2 it becomes necessary at the receiving end 39 of the cable to receive this series of signals and separate the signals into their original form of two distinct series. At 40 is indicated any usual type of receiving apparatus including means for driving the gear wheel 41 synchronously with the arriving signals (say one revolution for each of the elements a, b, c, d etc. of the signals Σ in Figure 1). By means of gear 42 the shaft 43 is driven at one-fifth the speed of the arriving signals, which is again the greatest common divisor of the speeds in the separate channels. At 46 is a disc similar to disc r' in the transmitting unit except that it carries five selectors a₂, b₂, c₂, d₂ and e₂ instead of the two selectors on R'. Magnet 45 receives the signals over leads 44 from receiver 40, and the successive signal elements a, b, c, d and e of signals Σ in Figure 1 therefore operate on the respective selectors a₂, b₂, c₂, d₂, and e₂ in exactly the same manner as was described in connection with disc R' and its selectors b and d with reference to signals X in Figure 1.

At 47' is a disc or frame similar to disc 27 except that only two equally spaced magnet and transmitting-pin mechanisms b and d are required, the latter co-acting with key system 48' similar to key system 25. A second disc 47'' carries three equally spaced magnet-operated transmitting-pin mechanisms a₃, b₃, and e₃ co-acting with key system 48''. The several transmitting pins a₃, b₃, c₃, and e₃ carried on these two discs 47' and 47'' are set into operative position by the respective selectors a₂, b₂, c₂, d₂, and e₂ of disc 46. These latter being controlled by the successive signal elements a, b, c, d, and e of the signals Σ in Figure 1, which latter in turn represent the respective signal elements of the separate signal series X and C of Figure 1, it is apparent that the key

mechanisms 48' and 48'' will be operated upon by the transmitting pins so as to send out over leads 49' and 49'' signals corresponding with the respective series of signals X and C in Figure 1 which were originally combined and introduced into the single cable 38.

The separation into three separate circuits of a combination of three series of signals would require the addition of one more disc similar to discs 47' and 47'' carrying the appropriate number of transmitting pins.

If cable 38 terminates at an intermediate station where only a process of relaying into another cable is required, then this can be done to the combined series (Σ in Fig. 1) without the need of separating, which need only be done at the terminus where use is desired to be made of the intelligible separate series of originals. Such series of signals appearing at leads 49' and 49'' can thereafter be utilized in any desired manner well known in the art.

The system described in connection with Figure 3 comprises a number of sets of magnetically operated selectors and their attendant magnetically operated transmitting mechanisms, each selector controlling a transmitting mechanism. If preferred mechanical means instead of electro-magnetic may be utilized, and one such equivalent is shown in Figures 7 and 8.

In Figure 7, gear 50 serves to drive shaft 51 carrying selector disc 52, transmitter disc 54 and selector or transmitter disc (as may be required) 53. The general manner of using this system is identical with that described in connection with Figures 2 and 3, so the description here is limited to a single transmitter, its controlling selector, and the receiving element which positions the selectors.

Dot signals arrive over leads 55 to excite electromagnet 56 and dash signals over leads 55' to excite electromagnet 56'. Armatures 57 and 57' are operated by the respective electro-magnets, and these armatures are extended in the form of a bell crank by respective members 60 and 60', the armatures being pivoted respectively at 75 and 75', held away from the magnets by springs 74 and 74' and having their respective motions limited by stops 58—59 and 58'—59'. At 63 is a shaft carrying little rotatable wheels 62 and 62' and the ends of armatures 60 and 60' are configured in a fork shape to engage in slots cut in the hubs of the respective wheels 62 and 62' so that motion of the members 60 and 60' under the action of their respective electro-magnets moves the respective wheels 62 and 62' along the shaft 63. The whole of the mechanism so far described, leading to the control of the position of the little wheels 62 and 62' along their shaft 63 by the signal currents in magnets in 56 and 56', is mounted

on frame 76 and fixed in space (but normally adjustable around the main shaft 61) so that the little wheels 62 and 62' are closely adjacent to the periphery of the rotating disc 52 which latter carries the selectors designed to actuate the transmitting pins.

Pivoted in the disc 52 is a T shaped member 66—66'—67, the pivot being at 68. A rod 69 is pivoted to the end of the arm 67 of this member and extends through the hollow shaft 51 to the disc 54 carrying the transmitting pin 72, and there the rod 69 is attached to one end of lever 70. Lever 70 is pivoted at 71 and its other end engages slot 71' of transmitter pin 72 so that upon motion of lever pin 72 is pushed out to one side or the other of disc 54 so as to engage either one of transmitting key levers 73 and 73'. These latter are arranged exactly as described in connection with Figures 5 and 6 so that the effect of pushing pin 72 out at one side of the disc is to send out a dot signal through the agency of lever 73, and the effect of pushing the pin 72 out at the other side of the disc is to send out a dash signal through the agency of lever 73'; and these positions of the pin 72 are consequent upon the motions of the arm 67 of the T shaped member in the selector disc 52.

At 64 in the selector disc 52 is a shaft which serves as a pivot for two driving members 65 and 65'. These driving members are positioned in front of the head ends of the two arms 66 and 66' so that when one of the little wheels 62 or 62' is moved along its shaft so that the disc of the wheel engages in the corresponding driver (65 or 65') the rotation of the system 52 moving the driver 65 (or 65') past the little wheel 62 causes the driver to be forced inward toward the shaft 51 and therefore press back the corresponding end 66 or 66' of the T shaped member. Figure 8 shows an end view of the driver 65, one of the little wheels 62, driver pivot 78 and part 66 of the T shaped lever. The main disc 52 carries the driver 65 and the drawing shows how the motion of the driver 65 past the fixed wheel 62 causes the driver to be forced in against the lever 66. Again referring to Figure 7, it is seen, therefore, that as described, dot current in magnet 56 attracts armature 57 so as to cause bell crank 60 to move wheel 62 in front of driver 65 so that the latter forces back arm 66 of lever 67 thus causing rod 69 to be moved to the right and transmitting pin 72 to the left. Similarly current in dash magnet causes wheel 62' to engage driver 65' and lever 66', thereby causing transmitting pin 72 to be moved to the left. A friction control at pivot 68 holds the lever 67, arm 69 and pin 72 in whatever position wheels 62 and 62' may leave it, but in order to ensure that the mechanism is in a neutral position ready to be effected by the next signal present in mag-

nets 56 and 56' there is provided a pair of fixed wheels (one of which is shown at 77 in Figure 8) arranged to act on the drivers 65 and 65' slightly in advance of the signal-controlled wheel 62 and 62'. These two fixed wheels are placed at such a distance from the main rotating disc 52 that one or the other of them acting on its corresponding deflected driving member as to restore same to a neutral position. In this connection, if wheel 62 depresses driver 65 for a dot signal then driver 65' will be forced outwards by lever 66' and it is upon driver 65' that one of the fixed wheels (77 of Figure 8) will act in restoring a neutral condition. In Figure 7 is shown a small tie rod or link 61 arranged so as to prevent both bell cranks 60 and 60' acting at once and thus damaging the apparatus by causing both of the wheels 62 and 62' to be positioned simultaneously. This might also be accomplished by using the stops 58, 58', 59 and 59' as electric contacts in conjunction with armatures 57 and 57', causing the circuit to each magnet 56 and 56' to be completed through the back stop contact, 58' or 58, respectively, of the other magnets armature.

Except for the difference in the mechanical arrangement the system described in connection with Figure 7 is equivalent to that described in connection with Figure 3. In both cases the manner of reception and segregation of the signals, indicated diagrammatically in Figure 2 is carried out in the same way, the two or more selector discs being replaced by a single disc carrying the total number of selectors, and the single transmitting disc being replaced by two (or more) transmitting discs having the total number of transmitting mechanisms distributed amongst them in the same way as the selectors are distributed amongst the several selector discs at the transmitting end of the cable circuit.

A mechanical equivalent of the systems shown in Figures 3 and 7, shown in Figure 9, and by the arrangement there shown the necessity of mounting moving mechanisms in or on the principal rotating member or shaft is avoided.

In Figure 9 at 79 and 80 are the two sources of signals, in this case, assumed to have speeds in the ratio 2:1; source 79 being at double the speed of source 80. Gearing 84 and 85 maintains this exact ratio of speeds, and the sources 79 and 80 may either be independent transmitters or, as shown in the figure, source 80 may be a transmitter and source 79 a receiving system for cable or receiving circuit 81. Gearing 86 and 87 drives shaft 88 in synchronism or sub-synchronism with these sources 79 and 80, and has mounted on it a number of cams later to be described.

Battery 89 supplies in common the local circuits from sources 79 and 80. In source 130

79 contact between members 83 and 83' constitutes a dot and between 83 and 83'' a dash. Dot current passes from battery 89 by way of lead 90, contact 83', lead 98', lead 105' magnet winding 106', of magnet P' and lead 107 to contact 108 thus completing the circuit through lead 97 when the cam follower 109 is pressed outwards by cam 104, and this is arranged so as to take place at about the middle of the time interval occupied by the signal, either by having cam 104 adjustable upon the shaft 88, or by having the contact system 108 and 109 adjustable about the shaft. Diametrically opposite the contact system 108 and 109 is another contact system 102 and 103 and the next signal emanating from source 79, say another dot, will cause current to flow from battery 89 by way of lead 90, contact 83' and lead 98' to branch lead 99' and thence to magnet 100' returning through lead 101, through contacts 102 and 103 and lead 97 to battery 89. The function of the contacts 102 and 108 is to cause the signals emanating from source 79 alternately to affect either magnet system P' and P'', or 100' and 100'' and the kind of signal (dot or dash) emanating from source 79 determines, through contact at 83' or 83'' and leads 98', 98'', 99', 99'', 105', and 105'', whether one of the dot magnets P' and 100' or one of the dash magnets P'' and 100'' will be acted upon, and the duration of the cam contact, determined by the length of the cam projection 104, determines the duration of the signal impulse delivered to the appropriate magnet.

Similarly, dot magnet 92' and dash magnet 92'' are controlled by signal source 80 through the relay contacts 82' and 82'', relay tongue 82, leads 91' and 92'', common leads 90 and 93, battery 89 and the cam operated contacts 94 and 95, the latter being operated by cam 96 so as to close momentarily at about the middle of the normal time of signal emanating from source 80.

The magnets P' and P'' have two windings 106', 124' and 106'', 124'' respectively arranged so that current in either winding is adequate to operate the armatures 110' and 110''. These armatures have a bell crank configuration with projecting levers 111' and 111'' respectively, are pivoted at 122' and 122'' respectively and controlled by springs 112' and 112'' respectively. The subsidiary windings 124' and 124'' are operated from battery 131 through cam contacts 128, 129, 132, 133, cam 130, and leads 125', 125'', 126, 127, through relay contacts 123' and 123'' operating in conjunction with the respective armatures 110' and 110'' so as to constitute the well known "flick and stick" circuits so as to retain either of the armatures 110' or 110'' after deflection in a deflected position until its "flick and stick" circuit is broken by the rotation of cam 130 opening its respective cam contact. The position of the cam 130 is

arranged so that this compulsory period of deflection is as nearly as practicable the period of rotation of shaft 88 and its attached cam 113. The "flick and stick" circuits are shown in dotted lines.

Co-acting with cam 113 is cam follower 114 mounted on spring 115 or equivalently. Bell cranks 119' and 119'', pivoted at 118' and 118'', carry projections 117' and 117'' positioned above cam follower 114 in such a way that when interposed pieces 116' and 116'' are pushed forward by their respective lever arms 111' and 111'' they are rotated about their respective pivots causing crank arms 119' and/or 119'' to move outwards against rearward projections 120' and 120'' of key contacts 139' and 139'' which latter are pivoted at 121' and 121'' respectively. Key contacts 139' and 139'' operate between their respective contacts 140', 141' and 140'', 141'' as ordinary cable code transmitting keys to send out cable code signals from battery 142 over leads 143 and 144.

The magnets 92'—92'' and 100'—100'' are mounted in relation to shaft 88 (although for sake of clearness not so shown in the drawing) in exactly the same way as magnets P' and P'' and through additional cams and interposed pieces serve to operate bell cranks 145', 145'', 146' and 146''; also co-acting with respective key levers 120' and 120'' exactly as has been described in connection with magnets P'' and P'. They are also provided with "flick and stick" circuits and auxiliary windings to be fed and operated by leads 136, 137, 138, cam 147 and cam-contact 132—133 and 134—135 in the same way as described in connection with magnets P' and P''.

The mechanism described in connection with Figure 9 achieves the same result as those described in connection with Figures 3 and 7. To adapt it to the separation of the combined signals into their component channels the system described in Figure 2 is followed, thereby retaining only one of the cams 104 and 96 but having the three contacts 95, 103 and 109 arranged equidistantly around the single cam. Further in place of the three pairs of bell cranks 119'—119'', 145'—145'', and 146'—146'' acting upon a single pair of keys 120'—120'' there would be provided two pairs of keys, one pair of which would be controlled by a single pair of bell cranks and the other pair of keys being controlled jointly by the two remaining pairs of bell cranks. Each pair of keys would then deliver the segregated signals over its separate output circuit.

A further equivalent as shown in Figure 10 eliminates the use of cam operated contacts and makes use of the simply constructed segmental slip rings instead.

In Figure 10, 148 and 149 are sources of signals, source 148 being at double the speed

- of 149. The two sources are maintained in synchronism as by gearing 150, and the shaft 161 is driven by gearing 151 at a speed equal to the center-hole speed of source 149. Key systems 152 and 153 in the two sources deliver dot signals over leads 152' and 153' and dash signals over leads 152'' and 153'' respectively over the circuit shown in full lines to relay systems L, M, and N, common battery 155 connected to lead 154 of the key systems completing the relay circuit through lead 156 and the conducting segments 157 and 158 with the associated brushes 162, 163, and 164 of the slip rings 159 and 160 mounted on shaft 161. The brushes are preferably made adjustable about the shaft so that they make contact with the conducting segments at about the middle of the respective signal elements. The relay systems L, M, and N, are all identical, each comprising dot and dash magnet, and each magnet provided with two independent electric contacts for example, as shown by means of separate armatures. Magnet system N is controlled by brush 162 on slip ring 159 and magnet systems L and M by brushes 163 and 164 respectively on slip ring 160. Each magnet provided with two independent windings, one as the main winding and the other to be used in association with one armature contact as a "flick and stick" circuit. All magnet systems being alike and dot and dash magnets operating similarly, it suffices to describe one magnet alone.
- In the figure the receiving or initial selector circuits are shown in full lines, the "flick and stick" circuits in dotted lines, and the output or transmitting circuits in dash lines. Assume a dash signal to arrive from source 148 by the completion of the circuit between key 152 and lead 152''. Nothing occurs until the conducting segment 158 passes beneath brush 164, whereupon main winding 165 of magnet M'' is energized from battery 155 over leads 152'', 166'', 166 and 156. Armatures 169 and 170 are deflected and make contact respectively at 170 and 168. Closure of contact 168 and armature 167 connects battery 180'' through resistance 181'', lead 179'', and lead 175 to the conducting segment M_o of slip ring 176, so that the passage of this segment beneath brush 177, consequent on rotation of shaft 161, causes a dash signal to be sent out over leads 173 and 182 to whatever circuit may be desired. The slip ring 176 carries three segments L_o, M_o, N_o, each controlled by the corresponding set of relays L, M, and N. Battery 180' through resistance 181' serves when a dot is to be transmitted over leads 178 and 182.
- When magnet M'' is energized as described, the armature 169 makes contact at 170 thus closing the circuit from battery 183 through leads 184 and 185, auxiliary magnet winding 186 contacts 169-170, lead 187, the armature 172, of dot magnet M', and its back stop 173, lead 188, brush 189 on conducting segment 190 of slip ring 191 and finally lead 193. The current thus produced in auxiliary winding 186 of magnet M'' holds both armatures deflected until the insulating segment 192 passes beneath brush 189 and thus opens the "flick and stick" circuit just described. The brush 189 is adjusted around the slip ring 191 so that this opening of the circuit and consequent release of the magnet armatures takes place shortly before conducting segment 158 again passes beneath brush 164 to effect the selection of the next but one signal element arising from source 148. The "flick and stick" circuits of dot and dash magnets M' and M'' are completed through both the back stops of their respective armatures in order to prevent both armatures being held in position if both should accidentally be deflected. Also resistances 181' and 181'' are introduced into the battery circuit in order to prevent short circuiting the battery 180'-180'' if both armatures 172 and 169 should be deflected simultaneously.
- Thus, in brief, during one complete cycle of operations embracing one signal element from source 149 and two from 148, the brushes 162, 163, and 164 allocate the three signal elements amongst the three pairs of selector magnets N, M and L respectively, the deflection of the magnet armatures effects connections between battery 180'-180'' and the respective slip ring segments N_o, M_o, and L_o so as to effect the retransmission therefrom at equally spaced intervals of the original three signal elements.
- At the other end of the system fed from leads 178 and 182 the segregation of the combined signals into the two separate channels can be accomplished by an arrangement of the apparatus in Figure 10 according to the principles shown in Figure 2. Thus, in place of the two slip rings 159 and 160, there would be provided only one, and the three brushes 162, 163 and 164 would be equally spaced around it. The slow speed-series of signals would then immediately be available from leads 182 and 194. For the double-speed series of signals slip ring 176 would be made with two equal segments by omitting segment N_o and lengthening, according to the percentage of marking desired, the two segments M_o and L_o, the latter then being equally spaced. The double-speed series of signals would then be available at terminals 178 and 182. If desired, in connection with the slow speed channel, another slip ring similar to 176, but carrying only one conducting segment connected to lead 194 would provide means for regulating the percentage of marking in this channel as well. In the case of signal speeds in the ratio 2:3, for example, it would be necessary to have a slip ring corresponding to 176 for each channel; the one having two and the other three segments.

It is obvious that, in the general operation of channel systems as herein described, the maintenance of synchronous running of apparatus at separated localities is necessary. 5 This can be obtained either by the use of apparatus for that purpose as described in U. S. patent application No. 671,136 or by the use of special alternating current synchronizing methods such as described in Patent No. 10 1,482,375 Frederick E. Pernot, Jan. 29, 1924.

Whilst in the embodiment of the invention described herein the speed of rotation of the controlling member (once for example as shaft 161 in Figure 10) has been assumed to 15 be equal to the greatest common divisor of the signal speeds in the respective circuits it is to be noted that the invention is in no way limited to this particular arrangement. If for example the speed of rotation of shaft 20 161 in Figure 10 is made equal to one half the greatest common divisor of the signal speeds in the respective circuits the apparatus will function in the manner described herein and without any change excepting that two interconnected diametrically opposite contact segments must be provided in each disc 159 and 160 in place respectively of the single segments 157 and 158; the two brushes 163 and 25 164 must be displaced by an angle of 90 instead of 180 degrees; two insulating segments must be used in place of the single segment 192, and six diametrically connected transmitting segments must be used in place of the three L_o, M_o, and N_o. Alternative charges 30 to those enumerated above can be made to 35 achieve the same effect.

It will be observed that in a multi-channel telegraphic system such as described the signal impulse speeds bear a fixed ratio one to another; that is to say, the speed of signalling in one channel has a fixed relation to the speed of signalling in the other channel or channels, and this makes it possible to employ continuous electric current, as from a battery, 40 throughout the system. In this respect the system herein described differs from those requiring the employment of alternating current.

Claims:

1. In a synchronous, multi-channel system of telegraphy a plurality of signal current generating and distributing devices, means for driving said devices at different interrelated speeds which are integral multiples 55 of some common fundamental speed, and means for aggregating the signal impulses of the several channels in appropriate interrelated ways for final utilization.

2. In a telegraph system a plurality of signal channels, said channels working at different signal impulse speeds, each of said speeds an integral multiple of some common fundamental speed and means for aggregating the signals of the several channels.

3. In a telegraph system a plurality of

signalling channels operating at different signal impulse speeds which bear a fixed ratio one to another, mechanism for aggregating the signals of the several channels, a moving member associated with said mechanism, said member repeating cyclic motions at a speed (frequency) equal to a common divisor of the individual signal speeds in the separate channels. 70

4. In a synchronous, multi-channel telegraph system a plurality of signal impulse generating and distributing apparatus, means for driving or operating said apparatus at different speeds bearing a fixed ratio one to another, means at any desired station for aggregating the signal impulses of the individual channel circuits, sets of selecting devices properly interrelated, the number of such sets being equal to the number of component circuits in operation, the number of selecting devices in the several sets having the same ratio as the respective speeds of individual circuits. 75

5. In an electric telegraph system a plurality of signalling channels, said channels working at different signal impulse speeds, means for aggregating the signals of the individual channels, sets of transmitting mechanisms, the number of said sets equal to the number of the individual circuits and the number of transmitting mechanisms in the several sets being in the same ratio as the respective speeds of the individual circuits. 90

6. In an electric telegraph system a plurality of signalling channels, said channels working at different signal impulse speeds, which bear a fixed ratio one to another, means for aggregating the signals of the individual channels, transmitting mechanism, a selector mechanism for each transmitting mechanism, the transmitting mechanisms set up by a corresponding selector mechanism so as to transmit the same kind of signal as originally actuated the selector mechanism. 100

7. In an electric telegraph system a plurality of signalling channels, said channels operating at different signal impulse speeds which bear a fixed ratio one to another, means for combining the signals of the individual channels, a set of selector mechanisms to each channel and each selector mechanism of each set actuated in turn by the signal elements present in the circuit pertaining to such set. 115

8. In a synchronous, multi-channel system of telegraphy, a plurality of signal current generating and distributing apparatus, means for operating said apparatus at different speeds bearing a fixed ratio one to another, and automatic means for combining the signals received over the individual signal channels, said means comprising selector mechanism operated automatically by fractions of each signal current. 120

9. In a synchronous, multi-channel system of telegraphy, a plurality of signal current 130

- generating and distributing apparatus, means for operating said apparatus at different speeds, which are integral multiples of some common fundamental speed, automatic means for aggregating at any desired point or points of the system the signal current impulses, means such as cables for transmitting the said aggregated signals, means for segregating at the receiving stations the signal impulses into the appropriate component transmission channels, selector and transmitting mechanism and means for temporarily storing the signals prior to ultimate transmission.
- 15 10. In an electric telegraph system a plurality of signalling channels, said channels working in synchronism and operating at different signal impulse speeds which bear a fixed ratio one to another, sets of selector mechanism for each channel, the number of mechanisms in each set being in the same ratio as the respective speeds of the channels, each selector mechanism comprising a unit for each type of signal element and said units 20 operating the transmitting mechanism, there being one transmitting mechanism for each selector mechanism.
